UNITED STATES PATENT OFFICE.

OLAV ESKIL JÖRGENSEN, OF COPENHAGEN, DENMARK.

COMPRESSED-AIR STARTING DEVICE.

1,372,028.

Specification of Letters Patent. Patented Mar. 22, 1921.

Application filed July 7, 1919. Serial No. 309,199.

To all whom it may concern:

Be it known that I, OLAV ESKIL JÖRGENSEN, of No. 16 Fredericiagade, Copenhagen, in the Kingdom of Denmark, a subject of the King of Denmark, have invented certain new and useful Improvements in Compressed-Air Starting Devices; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention refers to hydrocarbon motors, and the like, especially those of the Diesel type, of which the valves are moved by levers actuated from a cam-shaft and which are started and eventually reversed by admission of compressed air, or the like, to the cylinder through a special starting valve. As the moment of opening the starting-valve coincides or may coincide with the opening-moment of the fuel-valve, and as the cam of the latter differs from that of the former, not in situation but only in extent, the object of this invention is to work both starting and fuel valve with a common cam and a common lever mechanism having two points of engagement, one for the one, and another for the other valve, and being so constructed that, as needed, it can be caused to act with the one or the other of these points of engagement. A diagram of one form of construction is shown, by way of example, in the drawing, Figure 1 being a side view and Fig. 2 a plan with several details omitted. Fig. 3 is a modified form of construction.

The cam-wheel 1 actuates the roller 2 on the one arm of the valve lever 3, of which the other arm carries a special lever 4. On one side of its fulcrum 5, said lever presents a point of engagement 6 for the fuel-valve 7, and on the other side a point of engagement 8 for the starting valve 9, and at one side or the other it is held fast in a suitable manner, e. g. by means of a rod 10 connected with a head 11, which is loaded with a spring 12. As a consequence of this load, the special lever 4, owing to the movements of the main lever, will oscillate within such limits that the point of engagement 8 does not come into contact with the starting-valve, while the point of engagement 6 comes into con-

tact with and opens the fuel valve when the roller 2 touches the cam 13 or its most prominent part 14. This corresponds to normal working of the motor on fuel oil. 60

When the motor is to be started or reversed, the resistance of the spring 12, is overcome by means of a suitable hand-mechanism or a pneumatic, electric, hydraulic, or other mechanism, and the lever 4 is 65 brought into such a position as will bring the point of engagement 8 within and the point of engagement 6 outside of its sphere of action. This may, e. g., be accomplished by constructing the head 11 as a piston in 70 a special cylinder 15 for compressed air or other pressure medium. When this is admitted the load 12 is overcome, and the lever 4 is pressed upward until it strikes against a stop 16 on the main lever, so that, when 75 the cam 13, 14 actuates the main lever, the lever 4 oscillates, like a wholly or partially integral part of the main lever, at the same time the roller is brought farther down toward the cam so as to enable a more extended 80 cam to work the starting valve.

By means of this invention, a special cam as well as a special valve lever is saved, which is an essential advantage, both in itself and also because of economy of space. As 85 shown in Fig. 2, the valve may be symmetrically arranged on the cylinder cover. Thus the inlet valve 17 and the exhaust valve 18 may be symmetrically disposed one on each side of the fuel and starting valves, which 90 are placed according to a diameter; this arrangement allows room 19 for a water cooling between the valves 17 and 18.

Fig. 3 shows the modification that the stop (16) for the lever 4 is not arranged on the 95 lever 3, but on the rod 10 as flange 160 thereon. Furthermore the spring 12 is located partly inside the piston 11, in order to avoid projections above the surface of the cover. In this construction it is presumed that the 100 fuel valve opens outward, i. e. is opened by being lifted, and in order to make this possible there is between the point of engagement 6 and the valve rod 60 inserted a small lever 61.

The shown details are not essential for the nature of the invention and may be altered in many ways, depending upon whether the valves are opened by lifting or by being pressed down. The member 4 can 110 also be constructed in many other ways than as a two-armed lever.

I claim:

1. In a compressed air starting device, a fuel valve, a starting valve, a lever mechanism for operating both valves, a single cam for operating the lever mechanism, and pneumatically operated means for adjusting the lever mechanism, whereby one or the other of said valves will be actuated by said mechanism.
- 10 2. A compressed air starting device, comprising a fuel valve, a starting valve, a valve lever, an auxiliary lever carried thereby for engaging both valves, a rotary cam for actuating the valve lever, and means for controlling the levers whereby the fuel valve is actuated for the normal working of the motor.
- 20 3. A compressed air starting device, comprising a fuel valve, a starting valve, a valve lever, an auxiliary lever carried thereby for engaging both valves, a rotary cam for actuating the valve lever, means for controlling the levers whereby the fuel valve is actuated for the normal working of the motor,
- 25 and means for actuating the controlling means for operating the starting valve.
- 30 4. A compressed air starting device, comprising a fuel valve, a starting valve, a valve lever, a cam for rocking the latter, an auxiliary lever carried by the valve lever, means including the latter whereby the auxiliary lever actuates the fuel valve, and means for operating the last named means for moving the auxiliary lever into operative relation to
- 35 the starting valve.
5. A compressed air starting device, comprising a fuel valve, a starting valve, a valve

lever, a cam for rocking the latter, an auxiliary lever carried by the valve lever, means including the latter whereby the auxiliary lever actuates the fuel valve, and means for operating the last named means for moving the auxiliary lever out of operative relation to the fuel valve and into operative relation to the starting valve.

40 45 6. A compressed air starting device, comprising a fuel valve, a starting valve, a valve lever, a rotary cam for actuating the valve lever, and an actuating member operated by said valve lever and adjustable to actuate one or the other of said valves.

7. A compressed air starting device, comprising a fuel valve, a starting valve, a valve lever, a rotary cam for actuating the valve lever, an actuating member operated by said valve lever and adjustable to actuate one or the other of said valves, and means for adjusting said actuating member to determine which valve it shall actuate.

55 60 65 8. A compressed air starting device, comprising a fuel valve, a starting valve, a valve lever, a rotary cam for actuating the valve lever, an actuating member operated by said valve lever for actuating one or the other of said valves, controlling means for normally positioning said actuating member to actuate only the fuel valve, and means for varying the controlling means to position the actuating member to actuate only the starting valve.

70 In testimony that I claim the foregoing as my invention, I have signed my name.

OLAV ESKIL JÖRGENSEN.
